SPOON OR SIMILAR ARTICLE

Erik Nielsen, Oneida, N.Y., assignor to Oneida Ltd.,
Oneida, N.Y., a corporation of New York

Filed Dec. 3, 1962, Ser. No. 72,686

Term of patent 14 years

(Cl. D54—12)

FIG. 1 is a perspective front view of a spoon showing my new design;

FIG. 2 is a perspective back view of the spoon;

FIGS. 3 and 4 are, respectively, enlarged fragmentary front and rear views of the handle tip;

FIG. 5 is an enlarged end view thereof;

FIG. 6 is an enlarged fragmentary side elevation of the handle tip;

FIG. 7 is a section taken on line 7—7 of FIG. 3; and

FIG. 8 is a fragmentary section taken on line 8—8 of FIG. 3.

I claim:

The ornamental design for a spoon or similar article, substantially as shown.
